CLAIM

The ornamental design for a smart mirror, as shown and described.

DESCRIPTION

FIG. 1 is a perspective view of a smart mirror showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a cross-sectional view thereof, taken along line 9-9 in FIG. 3.

The dashed broken lines in the drawings illustrate the portions of the smart minor and form no part of the claimed design. The dot-dash broken lines in the drawings define the bound of an unclaimed area of the claimed design and form no part thereof.
